UNITED STATES PATENT OFFICE.

EDWARD H. PINKHAM, OF NORTH ANDOVER, MASSACHUSETTS.

HOLDER.

Application filed March 12, 1925. Serial No. 15,124.

To all whom it may concern:

Be it known that I, EDWARD H. PINKHAM, a citizen of the United States, residing at North Andover, in the county of Essex and

5 State of Massachusetts, have invented new and useful Improvements in Holders, of which the following is a specification.

This invention contemplates the provision of a container of novel construction, 10 primarily intended for stick shaving soap or the like, and designed to permit a soap to be quickly and conveniently fed from the container as desired, and conveniently re-filled when necessary.

15 The nature and advantages of the invention will be better understood when the following detailed description is read in connection with the accompanying drawing, the invention residing in the construction, 20 combination and arrangement of parts as claimed.

In the drawing forming part of this application, like numerals of reference indicate similar parts in the several views, and there- 25 in:

Figure 1 is a view in elevation of the container forming the subject matter of the invention.

Figure 2 is a view partly in section showing the manner in which the soap or other material is supported and fed to projected position for use.

Figure 3 is a perspective view of the stick holder.

35 Figure 4 is a perspective view of the follower.

The device forming the subject matter of the present invention comprises a holder for the stick shaving soap or the like and is preferably of the construction shown in Figure 3. While the holder may be constructed from any suitable material it essentially embodies a tubular portion 10 which is comparatively short, and relatively 40 movable curved portions 11 which are of a resilient character to allow the stick 12 of shaving soap or the like to be easily placed within the holder and held therein by the resilient action of the relatively movable 45 portions 11. The holder is formed with a flange 13 at the point of juncture between the tubular portion 10 and the relatively movable portions 11, and the periphery of this flange is knurled or roughened as at 14 to facilitate the use of the device in the manner hereinafter described. The relative-

ly movable portions 11 of the holder are formed with longitudinal slots 15 and these slots receive the lugs 16 which project from the follower 17 at diametrically opposite 60 points. In other words, the follower is arranged within the holder so that the lugs 16 project through the slots 15 thereof, the bottom of the stick of shaving soap or the like 12 reposes upon the follower 17 as shown in 65 Figure 2. The holder is also formed with an annular groove 18 immediately beneath the flange 13, to provide a swivel connection between the holder and the outer casing or container 19 in which the holder is ar- 70 ranged. This container 19 has its upper edge bent inwardly to lie within the groove 18 above referred to after the holder has been arranged within the container as shown in Figure 2. The body of the container is 75 corrugated to provide threads indicated at 20, while the outer ends of the lugs 16 are grooved as at 21 in a manner to accommodate said threads so that when the container 19 is turned while the holder is held sta- 80 tionary by the flange 13, the follower 17 is moved longitudinally of the holder to force the soap or the like a slight distance above the upper end of the holder for use. The follower 17 can of course be moved in either 85 direction within the holder depending upon the direction in which the container 19 is turned. The projected end of the soap is covered by a cap 22 when the device is not in use, which cap is adapted to repose upon 90 the flange 13 as shown in Figure 1. The device is not only simple in construction, and capable of being employed for the pur- 95 pose intended, but can be easily and conveniently refilled when it is found necessary to do so.

While it is believed that from the foregoing description, the nature and advantages of the invention will be readily apparent, I desire to have it understood that I 100 do not limit myself to what is herein shown and described, and that such changes may be resorted to when desired as fall within the scope of what is claimed.

Having thus described the invention, I 105 claim:

1. In combination, a container having threads, a shaving stick holder including relatively movable resilient portions adapt- 110 ed to be wholly positioned within the container, and a tubular portion projecting therefrom, and an annular groove at the

point of juncture between the tubular portion and the relatively movable portion, and upper end of said container being fitted to said groove, whereby said parts are rotatably associated, a follower arranged to align within the holder and upon which said stick reposes, and means associating the follower with the threads on the container, whereby the follower is operated incident to the rotation of the container with relation to the holder.

2. In combination, a container having threads, a shaving stick holder adapted to be received by the container and rotatably associated therewith, said holder including a

tubular portion projecting beyond one end of the container, and relatively movable resilient portions disposed within the container, said portions having longitudinal slots, a follower arranged to operate within the holder and upon which said stick reposes, lugs projecting from the follower through said slots and designed to engage the threads on the container, whereby said follower is operated incident to the rotation of the container and a cap adapted to close the tubular portion of the holder.

In testimony whereof I affix my signature.

EDWARD H. PINKHAM.
